FIG. 4

INVENTORS
JAMES S. JOHNSTON
MILLARD L. JOHNSTON
BY

Thomas L. Wilder

ATTORNEY

UNITED STATES PATENT OFFICE.

JAMES S. JOHNSTON AND MILLARD L. JOHNSTON, OF UTICA, NEW YORK, ASSIGNEES
TO CHARLES O. JONES, OF NEW HARTFORD, NEW YORK.

MUFFLER.

1,173,583.

Specification of Letters Patent. Patented Feb. 29, 1916.

Application filed October 4, 1913. Serial No. 798,362.

To all whom it may concern:

Be it known that we, JAMES S. JOHNSTON and MILLARD L. JOHNSTON, citizens of the United States, residing at Utica, in the county of Oneida and State of New York, have invented certain new and useful Improvements in Mufflers, of which the following is a specification, reference being had therein to the accompanying drawing.

10 Our invention relates to a muffler, and we declare the following to be a full, clear, concise and exact description thereof sufficient to enable anyone skilled in the art to which it appertains to make and use the same, reference being had to the accompanying drawings in which like reference characters refer to like parts throughout the specification.

The object of the invention is to provide a simple, efficient muffler for use in connection with internal explosive engines. The muffler is constructed to conduct the exhaust, as it comes from the engine, along a tortuous path that is adapted to give said exhaust a spiral whirl, whereby the sound of the escaping gases will be completely muffled without causing any back pressure on the engine.

Other features will be observed by referring to the drawings in which:

Figure 1 is a central section of the muffler; Fig. 2 is a central section of a modified form of the muffler; Fig. 3 is a perspective view of a tube employed in the muffler; Fig. 4 is a central section of a modified form of the muffler, drawn on a somewhat smaller scale than that of the foregoing figures.

Referring more particularly to the drawings, there is a center tube —1— which has a bore larger in diameter than the tube connecting the tube —1— with the exhaust pipe of the engine, so that the exhaust will not be impeded in any degree, when the same enters the tube —1—. The tube —1— is provided with apertures 2—2 and 3—3. The apertures 2 are disposed opposite each other at the ends of a diameter, which is

perpendicular to a diameter at the ends of which are disposed the apertures 3. Each two sets of the apertures 2—2 and 3—3 are 50 inclosed by a cylindrical casing 4 adapted to form with the disks 5 and the end members 6 and 7, the chambers about the tube —1—. The disks 5 are provided with the central apertures 9 and circumferential 55 peripheral grooves 10—10, in which fit the corresponding edges of the casings 4. The end members 6 and 7 have bosses 11 and 12, respectively and are held in place on the tube —1— by nuts 13 and 14, which are 60 threaded to the corresponding ends of the tube —1—. The end member 6 is also provided with an aperture 15 normally closed by a member 16. The member 16 is drawn outward, whereby to open the aperture 15, 65 by means of a cord or other suitable device 18, that is attached to a lever 19 located within convenient reach of the chauffeur's seat. The muffler is easily assembled by first disposing the disks 5 and end members 70 6 and 7 upon the tube —1—, placing the casings 4, so that their edges will engage the corresponding grooves of the disks 5 and then mounting the nuts 13 and 14 upon the tube —1—.

The operation of the muffler is effected in the manner following: The exhaust from the engine enters the tube —1— at the end 20 and passes, as indicated by the arrows along the tube —1— until it reaches the 80 apertures 2—2, its further progress along the tube —1— being prevented by the wall 21, whereupon, the exhaust enters the chamber 22, which allows the said exhaust to expand therein. From the chamber 22, the 85 exhaust reenters the tube —1— by way of the ports 3—3, and thence from the tube —1— to the chamber 23, to the tube —1—, to the chamber 24, to the tube —1—, to the atmosphere through the end 25 of the tube 90 1. In the event that it is desired to permit the exhaust to escape without passing through the tortuous path above described, or in order to effect a cut out of the muffler,

as when the automobile is ascending a hill or under a similar circumstance, the chauffeur manipulates the lever 19 and thereby opens the aperture 15 for the free passage 5 of the exhaust to the atmosphere.

Fig. 2, shows a muffler substantially similar in construction to that of Fig. 1. The casing 30 is secured in place by grooves 31 and 32 in the end members 33 and 34, respectively. The chambers 35, 36, and 37 are formed by the disks 38 and 39, which are held in position along the tube 40 by set screws or like means 41 mounted in the bosses 42 of the disks 38 and 39 and adapted to engage the surface of the tube 40. The end members 33 and 34 are held in position by the nuts 43 and 44 screw mounted to the ends of the tube 40. The means for permitting the exhaust to escape without passing through the tortuous path, which is similar in this instance to that of the former construction, comprises walls 45 disposed at suitable intervals along the tube 40, and having ports 46 that are normally closed by 15 the valves 47 secured to a common rod 48 held normally in the position shown in Fig. 2 by the coiled spring 49, which bears at one end against the member 50, whose opposite ends are secured to the nut 44, and the other 20 end against the pin 51. The rod 48 is actuated longitudinally, whereby to move the valves 47 away from the ports 46, so as to effect a straight passage to the atmosphere for the exhaust, by the member 52 having 25 an arm 53 and held to the rod 48 by the pins 51 and 54. The member 53 is connected by a chain or other device 55 with a lever 56 located near the seat of the chauffeur.

Fig. 4 illustrates a further modification 40 embodying a central tube 60 which comprises the member 61 having integral or otherwise secured thereto a disk 62. The said member 61 is also provided with partitions 63—63 and is adapted to detachably 45 hold the adjacent ends of the members 64 and 65, which are provided in an integral manner or otherwise, with the end members 66 and 67, respectively. The casing 68 is assembled by disposing its edges in the 50 grooves 69 and 70 of the end members 66 and 67. The muffler is held in assembled position by the rods 71 and the nuts 72. In operation, the exhaust enters by way of the end 55 73 and proceeds along the member 64 to the ports 74—74, oppositely disposed; to the chamber 75; to the member 61 by way of the ports 76—76; to the ports 77—77; to the chamber 78; to the member 65, by way of the ports 79—79, and out through the end 80 60 of the tube 60 to the atmosphere. This last described construction is of importance because of its knockdown feature and the quick manner in which the parts can be as-

sembled, so also may a like remark be made concerning the foregoing constructions, to a 65 somewhat lesser extent.

The parts of the muffler shown in the various modifications may be duplicated to a greater or less extent in accordance with the desire of the user, all of which we consider 70 within the scope of this invention.

Having thus described our invention, what we claim as new and desire to secure by Letters Patent is:

1. In a muffler, the combination of a tube, 75 chambers formed about said tube, apertures disposed opposite each other in pairs in said tube, whereby the exhaust from an engine may progress from one chamber to the other, and means for permitting said exhaust to 80 progress directly through said tube.

2. In a muffler, the combination of a tube, apertures disposed opposite each other in pairs in said tube, partition walls in said tube, ports in said walls, chambers formed 85 about said tube, and valves for closing said ports in the partition walls of said tube.

3. In a muffler, the combination of a tube, apertures disposed opposite each other in pairs in said tube, partition walls in said 90 tube, ports in said walls, valves for closing said ports, means for operating said valves, and chambers about said tube.

4. In a muffler, the combination of a tube, 95 partition walls in said tube, ports in said partition walls, valves for closing said ports, a rod connecting said valves, and a spring for holding said rod normally in such position as to close the valves.

5. In a muffler, the combination of a tube, 100 apertures disposed opposite each other in pairs in said tube, partition walls in said tube, ports in said partition walls, valves for closing said ports, a spring for automatically closing said valves, and chambers 105 about said tube.

6. In a muffler, the combination of a tube, apertures disposed opposite each other in pairs in said tube, partition walls in said tube, ports in said partition walls, valves for closing said ports, a rod attached to said 110 valves, and automatic means for actuating said rod, whereby to close said valves.

7. In a muffler, the combination of a tube, apertures disposed opposite each other in 115 pairs in said tube, partition walls in said tube, ports in said partition walls, valves for closing said ports, a rod attached to said valves, spring means for actuating said rod, whereby to close said valves, and means for 120 actuating said rod, whereby to open said valves.

8. In a muffler of the character described, the combination of a tube, apertures disposed opposite each other in pairs in said 125 tube, chambers formed about said tube,

valves for closing said tube, a rod attached to said valves, spring means for actuating said rod, whereby to close said valves, and means for actuating said rod, whereby to

5 open said valves.

9. In a muffler, the combination of a tube, apertures in said tube, chambers formed about said tube, valves for closing said tube, a rod attached to said valves, spring means

10 for actuating said rod, whereby to normally close said valves, a member passing through

said chambers and connected to said rod, and means for actuating said member, whereby to move said rod to open the ports, substantially as described.

15

In testimony whereof we have affixed our signatures in the presence of two witnesses.

JAMES S. JOHNSTON.

MILLARD L. JOHNSTON.
